UNITED STATES PATENT OFFICE.

GORDON MCKAY, OF CAMBRIDGE, MASSACHUSETTS.

NAIL-DRIVING MECHANISM FOR BOOTS AND SHOES.

SPECIFICATION forming part of Letters Patent No. 241,814, dated May 24, 1881.

Application filed March 29, 1881. (No model.)

To all whom it may concern:

Be it known that I, GORDON MCKAY, of Cambridge, county of Middlesex, State of Massachusetts, have invented Improvements in 5 Nail-Driving Mechanism for Boots and Shoes, of which the following description, in connection with the accompanying drawings, is a specification.

This invention has for its object the production of a mechanism for driving nails in soles of boots and shoes. United States Letters Patent No. 189,834 and No. 189,837, heretofore granted to Lyman R. Blake, show and describe a nail partially inserted into a sole, to be subsequently driven through the said sole and the edges of the upper of the boot or shoe into the usual inner sole, the points of the nails being clinched upon an iron or metal shoe-last.

The mechanism the subject of this invention was devised to drive nails partially inserted in the sole, as represented in the said patents.

In this invention I employed a stop, against which the side of the nail is brought or pressed just prior to the descent of a hammer which drives the said nail below the edge of the stop, whereby the sole is so unobstructed that it may be fed forward for a distance sufficient to bring the side of the next nail against the stop, when the first nail is driven below the stop, and the same operation repeated. The sole, as herein represented, is fed forward mainly by means of a feed-wheel, having preferably an india-rubber or other friction surface which acts against the edge of the sole pressed against the feed-wheel by the operator, who holds the shoe in his hand, or supported by a jack common in pegging-machines.

Figure 1 is a side elevation of a sufficient portion of a nailing-machine to illustrate my invention. Fig. 2 is a top view thereof; and Figs. 3 and 4 are details, to be referred to.

In the drawings, A represents the framework, having suitable standards *a* to form bearings for a shaft, *b*, driven by power applied to a pulley, *c*, the said shaft having secured to it a large cam, *d*, and a worm, *e*. This framework has also standards *f*, to receive a rock-shaft or pin, *g*, which serves as the fulcrum for 50 the hammer-arm *h*, the forward end of which

is provided with a hammer, *i*, secured thereto by the nut *j* applied to the hammer-shaft extended through a socket at the end of the arm *h*. The hammer-arm *h* derives its motion from the cam *d*, a stud, *l*, or roll carried by the said arm entering a groove in the cam *d*.

The feed device *m*, preferably a wheel having an india-rubber or flexible friction surface or periphery, is mounted upon a short shaft, *n*, having at its lower end a bevel-gear, *o*, which is engaged and driven continuously by a bevel-gear, *p*, on the inclined shaft *q*, it having at its other end a worm-gear, *r*, which is driven by the worm *e* on the shaft *b*.

The last *s* (represented in Fig. 1) has an upper and inner sole applied thereto, and an outer sole, *t*, placed in connection therewith, as usual, the outer sole having set up and partially driven into it a series of nails, *u*, as provided for in the patents hereinbefore referred to.

When a shoe the sole of which is provided with nails partially driven is to have the said nails fully driven into it and through the edge of the upper and through the inner sole, to be clinched upon the iron or metal-shod last, the 75 shoe held in the hands of the operator or supported on a jack, like that used in pegging-machines, is pressed against the edge of the feed-wheel *m*, which latter acts to move the shoe horizontally until the side of the nail next to 80 be driven meets the stop *w*, as shown in Fig. 3, when the hammer is made to descend, strike the head of and drive the nail into the sole. As soon as the head of the nail is so driven below the stop the feed-wheel immediately 85 causes the shoe to be again fed forward in the direction of the arrow, Fig. 3, until the next nail meets the side of the stop, when it is again driven by the hammer, and so on.

It is a part of my invention to use the nails 90 set in the soles for holding the sole in place, or what is technically called "laying the out-sole" by driving, by hand or otherwise, one or more nails on the sides and the toe and shanks of the shoes, and leaving the others to be 95 driven by a machine. When so used the feed has a peculiar operation, which is to carry the shoe beyond the driven nail and bring the next one not driven under the action of the hammer.

The feed-wheel *m* is, it will be noticed, ro- 100

tated continuously, and feeds the shoe, when the shoe is free to move, and slips on the edge of the sole when the movement of the shoe is arrested.

5 In order that the action of the feeding mechanism may not be interrupted by incompletely-driven nails, or any roughness on the head of the nail, I have provided a recess or slot, *v*, in the under side of the stop *w*, which allows no such obstructions to pass the stop, as shown in Fig. 3. This recess or slot in the stop is made bell-mouthed in shape at the side next the hammer, to insure ready entrance of the head therein.

15 It is obvious that the hammer may be actuated by a spring to give the blow, and lifted by a cam, as is common in pegging and nailing machines.

I claim—

20 1. In a machine for driving nails, as described, the stop to arrest the nail and the material in which it has been partially driven under the hammer, in position to be farther or completely driven, combined with a hammer and means, substantially as described, to operate it, as set forth.

25 2. The hammer and means to operate it, substantially as described, and a stop to ar-

rest the nail, combined with the feed-wheel *m*, against which the material is pressed and by 30 which it is fed forward, substantially as described.

3. In a machine for driving nails, the feed-wheel *m* and its shaft, and means to rotate it, combined with the hammer and hammer-carrying lever, having its fulcrum at right angles to the axis of the feed-wheel, and the cam to operate the hammer-lever, substantially as described.

4. The continuously-moving feed-wheel, substantially as described, to feed the shoe when the shoe is free to move, and to slip on the shoe when the movement of the latter is arrested.

5. In a nailing-machine, the stop *w*, provided with the recess *v*, substantially as and for the purpose described.

6. In a nailing-machine, the stop *w*, having the recess provided with the bell-shaped mouth. In testimony whereof I have signed my name 50 to this specification in the presence of two subscribing witnesses.

GORDON MCKAY.
